UNITED STATES PATENT OFFICE.

MORTON F. JUDD, OF STRATFORD, CONNECTICUT, ASSIGNOR TO THE RAYBESTOS COMPANY, OF BRIDGEPORT, CONNECTICUT, A CORPORATION OF CONNECTICUT.

AUTOMOBILE TRANSMISSION.

Application filed July 12, 1926. Serial No. 121,777.

This invention relates to transmission devices for automobiles, and especially to the Ford type of transmissions.

It is well known that the Ford type of transmission comprises three rotating drums, one for the low speed, the reverse and brake respectively, located closely adjacent each other and enclosed in a casing including a cover comprising substantially the entire upper half of the casing, and which cover has a small opening in the top thereof over these drums which is closed by a hand plate. Each drum is substantially encircled by a flexible steel band lined with asbestos or other suitable material, and is provided at its ends with forked or apertured ears engaged by an operating rod connected to the familiar operating pedal for clamping the band about its drum. It is obvious that after the mechanism has been in use for some time the asbestos or other lining for the bands wear out and must be renewed. Owing to the peculiar construction of the transmission and transmission cover, in order to replace any of the linings it is necessary to remove and replace the entire transmission cover, an operation which requires considerable skill and time.

In order to overcome these objections I have devised a new construction for these bands and the operating mechanism therefor which will permit their easy removal and insertion through the hand opening in the top of the transmission casing.

In the usual Ford type of transmission the operating mechanism for the band comprises an element adjustably mounted in one side of the casing and forming an abutment at its inner end for one of the ears of the band, a rotatable and slideable element extends through the other side of the casing and the other ear of the band and projects at its free end into a socket in the inner end of the adjustable member, and a coiled spring embraces the second element and is supported thereby between the free ears of the band, which spring engages the ears at the opposite ends thereof and tends to separate them to unclamp the band from the drum. In my improved construction I have done away with the second element extending between the ears of the band to support the spring, and thus leave this space free for removal of the band, except that

this second element is merely extended a short distance through the ear on its side of the band and is embraced by one end of the spring, the other end of the spring being reduced in diameter for a certain length 60 which passes through the other ear of the band and into the socket of the adjustable member.

Referring to the accompanying drawing forming a part of this specification, in 65 which similar reference characters are employed throughout the various figures to indicate corresponding elements,

Fig. 1 is a top plan view of a portion of a casing for a transmission of the type 70 mentioned with the hand hole cover removed and portions being broken away to more clearly show the construction. In this figure, however, only one of the rotary drums and the band therefor is shown, the 75 other two being omitted for greater clearness of illustration.

Fig. 2 is a side elevation of the upper portion of a drum, the band and the operating mechanism therefor, and 80

Fig. 3 is a side elevation of my improved spring construction.

In this type of transmission, as is well known, there are three drums placed side by side, the forward drum being the reverse drum, the central drum the low speed drum, and the rear drum the brake drum. I have, however, merely shown the central or low speed drum 10 and have omitted the other drums as the same construction of 90 band and operating means therefor may be used for all three drums. The transmission band comprises a strip of flexible steel 11 having forked or apertured ears 12 secured to the opposite ends thereof to receive the 95 operating mechanism for clamping the band about the drum. In the present instance, there is a member 13 adjustably mounted in the casing 14 by suitable screw threads, and it is normally stationary and engages the right hand ear 12 of the band at its inner end to form a normally stationary abutment for this ear. The member 13 may, of course, be adjusted in or out in the casing 100 to adjust the position of the band by rotation thereof through a suitable tool engaging the outer non-circular end 15 and after adjustment may be locked in adjusted position by the lock nut 16. At its inner end 105 this member is provided with a socket 17

opening from this end for a purpose presently to be described.

On the other side of the casing is a rod 18 rotatably mounted in the bearing 19 in the casing, and it is connected at its outer end to an operating pedal 20 for rotating this rod. Inside the casing is a stationary element 21 having a cam surface 22 cooperating with a correspondingly shaped cam surface on a collar 23 secured to the rod 18 by any suitable means, as a tapered pin 24. The rod 18 extends through the left hand ear 12 of the band and projects a short distance on the inner side thereof, as shown at 25. It will be apparent from an inspection of the drawing that this leaves a free space between the ears of the band so that the band may be easily withdrawn through this space, and to facilitate this easy removal or insertion of the band either one or both of the ears 12 may be detachably secured to the band by any suitable means, such as that disclosed in the patent to Ross #1,543,523, dated June 23, 1925. This securing means 25 comprises studs 29 on the band extending through openings in the body of the ear 12, and a rotatable button 30 mounted on the band in position to pass through an elongated opening 31 in the body of the ear 30 and adapted to be turned to a position to overhang this body and lock the ear to the band.

Inserted between the ears 12 of the band is a spring of peculiar construction. As indicated in Fig. 3, this spring is a helical spring having a body portion 26 of a given diameter larger than the apertures through the ears 12, so that when the spring is inserted between these ears the opposite ends 40 of this body portion will engage the inner sides of the ears and tend to separate them. At one end the spring is reduced in diameter, as shown at 27, so that it may pass through the aperture in the right hand ear 45 12 and into the socket 17 in the adjustable member 18. This reduced portion of the spring holds the right hand ear 12 of the band in proper position against the inner end of the member 18. At its other end the 50 spring embraces the projecting end 25 of the operating rod 18 which acts to hold the left hand ear 12 in the proper position.

In operation, forcing the upper portion of the pedal 20 forwardly with the foot will 55 turn the rod 18 in its bearing and with it the collar 23 carrying the cam surface. Cooperation of this cam surface with that on the stationary element 21 will force the rod inwardly or to the right, as viewed in 60 Figs. 1 and 2, and with it the left hand ear 12. The right hand ear 12 will be held stationary by the member 18, and therefore, the band will be clamped about the drum, the force of the clamping action depending, of course, on the amount of turn- 65

ing movement imparted to the rod 18. This action will compress the body portion 26 of the spring, and when the force on the pedal is removed the spring will separate the ears of the band to unclamp it from the drum. In removing the band the member 18 is moved outwardly in its mounting in the casing and then the spring 26 may be removed. The band is now free and the removable ear 12 may be detached therefrom and the band easily withdrawn from its position around the drum in the casing by merely withdrawing the other ear upwardly through the opening 28 in the casing. Of course, the insertion of the new band merely involves the reversal of this operation.

Having thus set forth the nature of my invention, what I claim is:

1. In a transmission, a transmission band provided with apertured ears at its ends, an abutment engaging one of the ears and provided with a socket at its inner end, a bar extending through the other ear having an abutment to engage the same and mounted for rotary and sliding movements, and a coiled spring between the ears tending to separate the same, said spring being supported by the bar at one end and having a reduced portion at the other end extending through the ear and into said socket.

2. In a transmission, a transmission band provided with apertured ears at its ends, actuating means for said band comprising members engaging the outer sides of the ears, one of said members having a socket at its inner end and the other an extension projecting through the aperture in one of the ears, and a coiled spring between the ears embracing said extension at one end and having a reduced portion at its other end extending through the other ear and into said socket.

3. An automobile transmission comprising a drum, a split band embracing the drum, apertured ears upon the ends of the band, means for actuating the band to and from clutching engagement with the drum including a pair of members engaging the outer sides of the ears, one of said members having a socket leading from its inner end and the other member having an extension projecting through one of the ears, and a coiled spring between the ears tending to separate them, said spring embracing said extension at one end and provided with a reduced portion at its other end extending through the other ear into said socket.

4. In an automobile transmission device, a casing, a rotary drum in said casing, a flexible transmission band embracing said drum and provided with ears at its opposite ends, a member adjustably mounted in the casing forming an abutment for one of said ears and having a socket leading from its

inner end, a spring between said ears tending to separate them and having a reduced portion at one end extending into said socket, a support for the other end of the 5 spring mounted to slide in the casing and forming an abutment for the other ear, and means for sliding said support.

5. In an automobile transmission device, a casing, a rotary drum in said casing, a 10 flexible transmission band embracing said drum and having ears at its opposite ends, a member adjustably mounted on the casing forming an abutment for one of said ears and having a socket in its inner end, a bar 15 extending through the other ear and mounted for rotary and sliding movements in the casing, an abutment carried by said bar for the latter ear, a coiled spring between the ears tending to separate them, 20 said spring embracing said bar at one end and provided with a reduced portion at its opposite end extending into said socket, means for giving a sliding movement to the

bar upon rotation thereof, and means for turning said bar.

6. In a transmission, a transmission band 25 provided with ears, and actuating means for said band including a helical spring reduced in diameter for a portion of its length to form an abutment, said spring being located 30 between the ears and tending to separate the same, and supporting members engaging the outer sides of the ears and forming supports for said spring.

7. In a transmission, a transmission band 35 provided with ears, and actuating means for said band including a helical spring reduced in diameter at one end to extend into one of said ears and form an abutment to engage the inner side of said ear, said spring being 40 located between the ears and tending to separate them, and supporting members providing abutments for the outer sides of the ears and forming supports for said spring.

In testimony whereof I affix my signature.
MORTON F. JUDD.
